A. L. POWELL

INTERNAL COMBUSTION ENGINE

Original Filed Feb. 2, 1921

Inventor

A. L. Powell

UNITED STATES PATENT OFFICE.

ALVAH L. POWELL, OF MILES CITY, MONTANA, ASSIGNOR TO THE A. L. POWELL POWER CO., INC., OF MILES CITY, MONTANA, A BODY CORPORATE.

INTERNAL-COMBUSTION ENGINE.

Application filed February 2, 1921. Serial No. 441,975. Renewed August 17, 1923.

To all whom it may concern:

Be it known that I, ALVAH L. POWELL, a citizen of the United States, residing at Miles City, in the county of Custer and State of Montana, have invented certain new and useful Improvements in Internal-Combustion Engines, of which the following is a specification.

My invention relates to improvements in internal combustion engines in which I effect ignition by a novel arrangement of compressing members, firing a small quantity of the intaken firing charge in a separate compressing chamber, and exhausting the fired minor charge into larger combustion spaces where regular power charges are fired by the said exhaust from the smaller charge. The ignition of the lesser charge I obtain by mechanical compression, as hereinafter to be described.

In the accompanying drawings I show an engine equipped with my improvement. In these

Fig. 1 is a vertical elevation, in section.

Fig. 2 is a vertical elevation in section, taken at right angles to that given in Fig. 1.

Fig. 3 is a cross section on line 3—3.

In a cylinder, A, Fig. 1, there are two slidable pistons, A¹, A². Piston A² is connected by a wrist pin, A¹⁰ to a rod, B², said rod engaging a crank B¹ by a crank pin, B. Piston A¹ is connected by similar members, to a power shaft, not shown. At a point preferably central to the positions of said pistons there are located a piston A⁴, and piston A³. A⁴ terminates in a male extension, A⁵, Fig. 1, that fits, slidably, in a counterbore in A³. The pistons A³, A⁴, are normally held in the position shown in Fig. 1, by a spring, A⁶. In the head of A⁴ there is a valve fitting on a valve seat, as shown. A similar valve in head of piston A³ is indicated by A⁷, Fig. 1. It will be observed that the male extension of piston A⁴ acts as a piston in a minor chamber, C, and that a hole runs through the piston A⁴, opening into the chamber under valve A⁷. A similar hole, C¹, in piston A³ opens into chamber C², and into valve space over valve A⁶. Pins A⁸, A⁹, A¹⁰, A¹¹, in the walls of A project into an annular space in piston A³, A⁴, and allow

for a movement of said pistons, hereinafter described.

Assuming that a power stroke has just taken place, the operation of the engine is as follows:

On instroke of pistons A¹, A², exhaust takes place through operable valves D, D¹, Fig. 2. At end of this stroke pistons A¹, A², hit the lugs D⁴, D⁵, on pistons A³, A⁴, compressing spring A⁶. At the same time the tappets on the stems of valves A⁶, A⁷, are also pressed by the power pistons, opening said valves. On outstroke, that is, on suction stroke of A¹, A², valves A⁶, A⁷, are released and the tension of spring A⁶ forces pistons A³, A⁴ apart. At this time operable inlet valves (Fig. 2) are open and a fresh charge is being drawn in. As a condition of partial vacuum has been induced in chamber C, the valves A⁶, A⁷ remain open for an instant, and part of the incoming fuel charge enters said space. On restoration of pressure equilibrium, valves A⁶, A⁷, reseat. On compression stroke of pistons A¹, A², the fresh charge is compressed. An inspection of the drawing, Fig. 1, will disclose that the total compression on the larger area of pistons A³, A⁴, is concentrated on an area equal to the minor diameter of A⁴. The compression of the minor charge in C will, therefore, be much greater than that in the power combustion chambers. The chamber C is proportioned, in depth, to make possible extremely high compression, that is, to five hundred or more pounds to the square inch. The charge within is compressed to a degree where it spontaneously explodes and this, in a properly proportioned engine, will coincide with the position of power pistons, A¹, A², at a point near extreme of instroke. The said pistons will then depress valves A⁶, A⁷, and the hot charge from chamber C¹ will exhaust into both combustion chambers, igniting the charges therein at a point substantially over crank center, or beginning of outstroke. In this way I effect an automatic and dependable ignition, derived from mechanically disposed members within the engine structure.

In walls A of cylinder I provide breathing holes, E, to allow for movement of pis-

tons A³, A⁴, without compression in the space F.

What I ask to have protected by Letters Patent is—

5 In an internal combustion engine, the combination of a power cylinder, a slideable power piston therein, a secondary piston having a male extension, a piston having a bore within which the said male extension 10 slidably fits, operable check valves in said pistons, a spring, means whereby the pres-

sure of said spring tends to force said pistons apart, means for introducing an explosive charge in the space between said check valves, means for intaking and compressing firing charges in the power cylinder, means for firing said charges by the heat of the exhaust of the minor compressed charge, and means for transmitting power to a crank shaft, substantially as described.

In testimony whereof I affix my signature.

ALVAH L. POWELL.
